(57) **CLAIM**

The ornamental design for a dash board and console for an automobile, as shown and described.

DESCRIPTION

FIG. 1 is a perspective view of a dash board and console for an automobile showing our new design;

FIG. 2 is a front view thereof;

FIG. 3 is a rear view thereof;

FIG. 4 is a right side elevation view thereof;

FIG. 5 is a left side elevation view thereof;

FIG. 6 is a top plan view thereof; and,

FIG. 7 is a bottom view thereof.

Our design includes a mirror image of the embodiment depicted.

The de-emphasized and halftone portions of the rear and bottom views of the dash board and console in FIGS. 3 and 7, respectively, illustrate environmental structure for the dash board and console for automobile that forms no part of the claimed design.
